UNITED STATES PATENT OFFICE

FRANK G. OKADA, OF DENVER, COLORADO

DESIGN FOR AN AUTOMOBILE

Application filed October 10, 1930. Serial No. 37,220. Term of patent 14 years.

To all whom it may concern:

Be it known that I, FRANK G. OKADA, a subject of the Emperor of Japan, residing in the United States of America, in the city and county of Denver and State of Colorado, have invented a new, original, and ornamental Design for an Automobile, of which the following is a specification, reference being had to the accompanying drawings, forming part thereof.

Fig. 1 is a top plan view of an automobile embodying my design; and

Fig. 2 is a side elevation thereof.

The characteristic features of this design are the upwardly and forwardly inclined windshield, the rearwardly inclined roof and the increased width of the body at the position of the front seat.

I claim:

The ornamental design for an automobile as shown and described.

In testimony whereof I affix my signature.

FRANK G. OKADA.
